APPARATUS FOR THE ELECTRICAL TREATMENT OF COLLOIDAL DISPERSIONS

Edward Arthur Murphy, Wylde Green, England, and Frederick James Paton and John Ansell, Batu Anam, Johore, assignors to Dunlop Rubber Company Limited, London, England, a company of Great Britain

Application November 15, 1941, Serial No. 419,258
In Great Britain April 19, 1940

4 Claims. (Cl. 204—301)

Our invention relates to apparatus for the electrical treatment of colloidal dispersions, that is, the treatment of purifying, separating or concentrating dispersions, suspensions or the like that are electro-creamable. Examples of such electro-creamable dispersions are dispersions of or containing pectin, gelatine, casein, dye-stuffs, metals and resins, such as rubber, in appropriate condition.

In the general term "rubber," the invention contemplates aqueous dispersions of or containing caoutchouc rubber, gutta percha, balata or similar vegetable resins occurring naturally, or artificially obtained, and either in unvulcanized or vulcanized condition. Aqueous dispersions of coagulated rubber, vulcanized rubber, synthetic rubber waste or reclaim may also be used if desired as alternatives or admixtures; and any of these dispersions may contain the usual compounding ingredients.

More particularly the invention relates to the electro-creaming of rubber latex in apparatus comprising a number or multiplicity of diaphragms between which such dispersions are submitted to a difference in electrical potential to effect the creaming.

As rubber latex is, therefore, an example of the above type of dispersion, the term "latex" is used hereinafter to designate the dispersion to be treated. The concentrate produced or obtained in the apparatus is called the "cream."

In our invention the period of time during which the apparatus may be operated efficiently without stopping is very greatly increased.

In our invention also we make provision whereby the individual diaphragms can be cleaned or replaced without interrupting the operation of the apparatus. The diaphragms are so arranged as to be readily removable from, and replaceable in, a vat or cell containing the latex. For this purpose a cell is preferably arranged in such a way that the diaphragms are readily accessible therein and the cell has an open top, or readily removable lid, to permit the diaphragms to be conveniently lifted.

To prevent a skin formation on a free surface of the latex, a surface disturber is provided to sweep through the surface. The above arrangement permits the use of weirs at the edge of the free surface over which weirs the cream descants.

In our apparatus the diaphragms are preferably pendent or hang freely and are completely submerged. Each may comprise a sheet of suitable permeable material, such as "Cellophane"

sheets. The top edge of each sheet carries a member which spans the cell or tank and has projecting ends that fit or rest in slots in the cell walls and thus supports the sheet in fixed position in the latex. The bottom edge of the sheet is weighted which causes the sheet to hang true in the latex. The upper supporting member and the lower weighting member are conveniently carried in tubular hems formed on the upper 10 and lower edges of the sheet respectively, or may be associated or combined with said sheet in any other suitable way. The bottom, weighting, member may comprise a simple rod, and the top, supporting, member may comprise a slat carrying lugs to facilitate handling.

To clean or replace a diaphragm that is becoming clogged, it is merely lifted out of the cell as, for example, by hand or mechanically, whereupon it may be cleaned or replaced by another.

In general, the diaphragms may be arranged in any one of the various ways as described in our co-pending application Serial No. 419,268, filed on even date herewith.

In using an open top cell in which the diaphragms are readily accessible, the cell may comprise a suitable receptacle or compartment partitioned adjacent each end wall to house the electrodes and provided adjacent each said wall with a slotted rack to support the diaphragms. A suitable loose lid may be provided if desired.

To disturb the surface and to prevent skin forming, a blade having one edge submerged in the latex may be reciprocated slowly along the cell by any suitable means as, for example, by a reversing screw and nut mechanism. Flanking each of the racks aforesaid is a weir over which the cream flows into longitudinal flumes which may deliver into a single transverse flume leading to a suitable container for the cream.

As the current acts on the latex the disturbed particles, such as rubber, float to the surface layers and collect there as a cream of the required consistency. This cream then flows over the weirs under the influence of a "head" of the supply feed. The surface disturber may aid in easing the cream over the weirs.

The latex is fed to the apparatus and the separated serum drawn away under suitable control means. For this purpose any of the known means in the art, such as a float chamber adjacent the head or meters to indicate the condition of the respective dispersions flow to and from the apparatus, may be used.

Various features of the invention are illustrated, by way of example, in the accompanying

drawing comprising a perspective view of an apparatus embodying the invention.

In the drawing a vat or cell or tank 1 is provided with a multiplicity of pendant diaphragms normally submerged below the liquid level in the vat or cell, one of which is shown as at 2, slightly raised from its submerged position. When in submerged position the diaphragms are supported by a supporting member 3 extending throughout the upper edge of the diaphragms and projecting therefrom on each side and supported in slots, a series of which are arranged as at 4, at each side of the tank or cell. A surface disturber 5 for preventing skin formation on the free surface of the latex is mounted so as to be reciprocated along the cell by the mechanism 6 comprising a reversing screw and nut. At each end of the vat or cell 1, a weir 7 is provided over which the cream may decant. To enable the diaphragms to be completely submerged and permit the disturbing member 5 to pass freely over their upper edges, the projecting ends of the supporting member 3 are extended outwardly and upwardly to form the lugs 8. This also facilitates the handling of the diaphragm.

Latex is supplied to the cell or tank through piping 9 and may be withdrawn from the bottom of the tank through a draw-off pipe 9a. The electric current for causing the creaming is supplied to electrodes 10 at the opposite ends of the vat or cell.

From the above it will be apparent that our invention provides apparatus in which the diaphragms are so held in freely pendant or suspended arrangement that any one of them may be lifted without disturbing the others and may be thus cleaned and replaced or substituted by another. Also the cream not only overflows into the weirs, but a uniform sweeping of the entire

surface over the weirs by the disturber 5 prevents any of the surface cream remaining to form a skin.

Having described our invention, what we claim

5 is:

1. Apparatus for the electrical treatment of colloidal dispersions comprising a container, a multiplicity of diaphragms suspended in spaced relation in said container, electrodes at opposite 10 ends of said container, weirs on opposite sides of said container and a blade movable in the liquid surface of said container alternately toward one and the other of said weirs.

15 2. Apparatus for the electrical treatment of colloidal dispersions comprising a container having overflow weirs, supply piping below the level of said weirs and draw-off piping below the level of said supply piping, a number of diaphragms suspended in said container in spaced position 20 and completely below the overflow level of said weirs, electrodes extending to said container and a blade moving in the level of the overflow of said weirs toward and from said weirs.

25 3. The apparatus of claim 2 in which said container is open.

30 4. Apparatus for the electric treatment of colloidal dispersions comprising a container having overflow weirs on opposite sides, diaphragms suspended in said container entirely below the level of said overflow weirs and in spaced parallel 35 relation between said overflow weirs, electrodes at opposite ends of said container, and means movable above the upper ends of said diaphragms at the overflow level of said weirs to move the surface of liquid therein toward said weirs.
